UNITED STATES PATENT OFFICE.

ALBERT L. STEARNS, OF NEW YORK, AND ADOLPH W. HOFMANN, OF BROOKLYN, NEW YORK, ASSIGNEES TO BOY WATCH CASE CO., OF NEW YORK, N. Y., A CORPORATION OF NEW YORK.

WATCHCASE FILLER RING.

Application filed July 7, 1922. Serial No. 573,276.

To all whom it may concern:

Be it known that we, ALBERT L. STEARNS and ADOLPH W. HOFMANN, both citizens of the United States, and residents, respectively, of the city of New York, borough of Manhattan, in the county and State of New York and the city of New York, borough of Brooklyn, in the county of Kings and State of New York, have invented a new and Improved Watchcase Filler Ring, of which the following is a full, clear, and exact description.

This invention relates to watches and particularly to an improved watch case and filler ring constructed to produce a pleasing appearance and at the same time utilize a small watch movement in a large case.

The object of the invention is to provide an improved construction of watch case wherein a thin case may be provided with a small set of works and present the appearance of large works in a large case.

Another object in view is to provide a watch case with a filling ring permanently fixed or removably positioned in the case to cover up the vacant space between the outer part of the case and the works.

A still further object of the invention is to provide a watch case capable of using small works for giving the appearance of large works with means for presenting a small dial or a large dial.

In the accompanying drawing—

Figure 1 is a plan view of a watch case disclosing the invention, suitable works being shown properly mounted in the case.

Figure 2 is a perspective view of the case open with the works moved to a position out of the bottom of the case.

Figure 3 is a view similar to Figure 1 but with the cover or lid open.

Figure 4 is an enlarged fragmentary sectional view through Figure 3 on line 4—4.

Figure 5 is a perspective view of the filling ring shown in Figures 1, 3 and 4.

Figure 6 is a view similar to Figure 3 but showing a different arrangement of dial.

Figure 7 is a view similar to Figure 1 but showing a modified construction.

Figure 8 is a perspective view of the watch shown in Figure 7 with the lid open and disclosing the way the filling ring is mounted.

Referring to the accompanying drawing by numerals, 11 indicates a casing of any de-

sired kind provided with a bottom section 12 and a lid 13. These two members, namely, the bottom 12 and lid 13 are of the usual construction and are hinged together in the usual manner. A member 14 which may be termed a frame is hinged to the bottom 12 at approximately 90° from the hinge supporting the lid 13, said frame having a bottom section 15 and a top section 16, said top section being provided with suitable apertures 17 for receiving the pins 18 of the filler ring 19. This filler ring may be gold or any suitable material and may be plain on the outer surface or may be provided with ornamentation 20 of a desirable kind. The frame 14 fits into the bottom 12 and substantially fills the same in the same manner that ordinary works would do. The frame 14 is provided with a central bore or opening 21 in which the watch works 22 are mounted in any desired manner so that the dial 23 will be substantially flush with the outer surface of ring 19.

In constructing very thin watch cases, it is necessary either to provide an especially constructed set of works or to provide the frame 14 shown in Figure 2 and then use the works 22 which are small. Most of the works of watches are made comparatively thick when designed for a man's watch, while small watches are particularly adapted for ladies and are made not only small but thin.

In the present method of manufacturing watch movements or works, expensive gigs and other machinery are used and to change these gigs and other machinery would be very expensive and in most cases prohibitive. However, there is a demand for thin watches for men and in order to produce thin watches without changing this expensive machinery, the frame 14 and associated parts are provided whereby a small movement may be used in a large case and give the appearance of a large movement. As all small watches are thin, the object is attained by using the movement of a small watch where such movement may be used without disclosing the fact that it is a small movement. The movements or works 22 may be secured in the frame 14 in any suitable manner and by reason of the filling ring 19 and the ornamentation thereon a properly appearing watch will be presented as shown in Figure 1 which will be of a proper size for men's use and at the same time will be very thin.

If desired, the ring 19 could be secured rigidly to the section 16 though ordinarily it is made separate as shown in the drawing. The forming of this ring separate has a great advantage in that it permits a jeweller to readily change the appearance of the watch at any time. If a purchaser should not like the ornamentation on ring 19 as it appears in Figure 1, the jeweller could remove the ring 10 and substitute another one having a desired ornamentation.

In Figure 6 a slightly different construction is disclosed wherein the ring 19 is provided with graduations 24 and suitable numbers 25 for forming a dial which dial is larger than that shown in Figure 1 by reason of the fact that it is on the ring 19 instead of on the face of the movement 22.

In Figures 7 and 8 a further modified form 20 of the invention is shown wherein the ring 19' is soldered or otherwise rigidly secured to the lid 13'. When the lid is closed the watch appears as shown in Figure 7 but when open it appears as shown in Figure 8. 25 In some instances, this structure is desirable but it will be noted that the ring 19' cannot be readily removed as in the case of the watch shown in Figures 1 to 4. However, in this form of the invention as well as in the form 30 shown in Figures 1 to 6, a filling ring is provided which will permit the use of a small set of works and at the same time give the appearance of a large set so as to comply with the demands of the trade in respect to 35 men's watches.

What we claim is:—

40 1. A watch, comprising a large thin case, a frame arranged in said case having an opening, a watch movement arranged in said opening, said movement being much smaller in diameter than the case, and covering means arranged on said frame around said movement and over the space between said movement and said case.

2. A watch case, comprising a bottom, a 45 lid, a frame formed with an opening for receiving a watch movement, said opening being of appreciably less diameter than the bottom and an annular covering member arranged between the watch movement receiving opening of the frame and the case. 50

3. A watch case, comprising a bottom, a lid, means for holding a small movement in said bottom, and a removable ornamental ring surrounding said movement, said ring 55 having an opening appreciably smaller than the case for receiving said small movement.

4. A watch case, comprising a bottom, a lid, means for holding the movement in said bottom, said means having an opening of 60 appreciably less diameter than the bottom so as to support a movement of appreciably less diameter than the casing, and a covering ring for filling the space between the movement and the outer edge of the casing, 65 said ring being removably mounted in the casing.

5. In a watch casing, a movement supporting frame having apertures, and a covering and filling ring having pins extending into 70 said apertures, said filling ring being removable.

6. In a watch casing, a movement supporting frame, said frame having an opening in the center appreciably smaller than the frame so as to receive small works, and a filling ring fitted over said frame with an opening corresponding with said works, said ring having adjacent said opening graduations indicating hours and fractions of hours 75 and also numbers adjacent the graduations indicating hours from one to twelve whereby the hands of said works may readily indicate on the dial formed by said graduations the correct time. 80

ALBERT L. STEARNS.
ADOLPH W. HOFMANN.
